DESIGN FOR A DRINKING FOUNTAIN FOR FOWLS

Richard R. Setzer, Kansas City, Mo.

Application February 7, 1944, Serial No. 112,500

Term of patent 7 years

(Cl. D12—2)

To all whom it may concern:

Be it known that I, Richard R. Setzer, a citizen of the United States of America and resident of Kansas City, in the county of Jackson and State of Missouri, have invented a new, original, and ornamental Design for a Drinking Fountain for Fowls, of which the following is a specification, reference being had to the accompanying drawing, forming part thereof, in which Fig. 1 is a side elevation of a drinking fountain for fowls, showing my new design. Fig. 2 is a top

view of the same. Fig. 3 is a view similar to Fig. 1 with the supply jar removed. Fig. 4 is a section on the line 4—4 of Fig. 3. Fig. 5 is an end elevation of what is shown in Fig. 1. Fig. 6 is a side elevation of the water supply jar inverted, as used, as it is shown in Fig. 1.

I claim:

The ornamental design for a drinking fountain for fowls, substantially as shown and described.

RICHARD R. SETZER.
